COMBINED DOOR LOCK AND AJAR HOOK

Henry G. Voight, New Haven, Conn., assignor to
Sargent & Company, New Haven, Conn., a corporation of Connecticut

Application May 6, 1942, Serial No. 441,911

12 Claims. (Cl. 70—93)

This invention relates to door locks, and more particularly to a combined door lock and "ajar hook," or a device for permitting the door to swing to partly open position but preventing it from being opened to a further extent. In connection with outside doors and doors to rooms or apartments, it is sometimes desirable to employ mechanism to permit the occupant to open the door to a limited extent, while at the same time preventing anyone from the outside from forcing the door to a further open position so that entry could be effected. The present invention is applied to a door lock of this character, and the mechanism shown in this application is an improvement on a similar type of door lock shown in my pending application Serial No. 425,331, filed January 1, 1942.

In the present application the lock is provided in addition to the latch bolt with an ajar or auxiliary bolt reciprocably mounted in the lock case, which bolt is adapted to be thrown to enter a slot in an element swingingly connected to the door jamb or strike plate, so that when this bolt is thrown the opening of the door will be limited by the length of the slot in the link.

Means is also provided for the withdrawal of the usual latch bolt when the auxiliary bolt is thrown, and as it is also desirable to dog the latch bolt against a forced retraction by an instrument inserted between the door and jamb, it is necessary to provide mechanism for moving this dogging member to inoperative position when the auxiliary bolt is thrown; so as to permit the retraction of the latch bolt.

In this respect the present application distinguishes from my prior application above referred to, in that in the present case the usual guard bolt and latch-bolt-dogging mechanism is provided, and also mechanism is arranged to move the dogging element to inoperative position, which mechanism is operated by the means which actuates the auxiliary bolt.

One object of the present invention is to provide a door lock having a latch bolt and latch-dogging mechanism, and an auxiliary bolt with means to protract the auxiliary bolt and simultaneously move the dogging means to inoperative position and retract the latch bolt.

A further object of the invention is to provide a door lock having a latch bolt and dogging means therefor, and an auxiliary bolt designed to be thrown, if desired, when the door is closed, and means operated by the throwing of the auxiliary bolt to move the dogging element to inoperative position and retract the latch bolt.

To these and other ends the invention consists in the novel features and combinations of parts to be hereinafter described and claimed.

In the accompanying drawings:

Fig. 1 is a front elevational view of a combined door lock and fastener mechanism embodying my invention, the cover of the lock case being removed to show the interior mechanism in the position it occupies when the door is closed;

Fig. 2 is a view similar to Fig. 1, showing the mechanism in the position occupied when the auxiliary bolt is protracted, some parts being omitted for the sake of clearness;

Fig. 3 is a view similar to Fig. 2, showing the position of the parts at the beginning of the retractive movement of the auxiliary bolt;

Fig. 4 is a face view of the door strike and fastener element;

Fig. 5 is a sectional view on line 5—5 of Fig. 2;

Fig. 6 is a sectional view on line 6—6 of Fig. 3; and

Fig. 7 is a sectional view of the outer end of the auxiliary or door-fastening bolt.

To illustrate a preferred embodiment of my invention, I have shown a door lock comprising a casing 10 having mounted therein a lock cylinder 11 of the usual form provided with a rotatable rollback 12. The casing also contains a latch bolt comprising a bolt head 13 and stem 14, guided by lugs 15 on the case, and normally urged to protracted position by a spring 16. At the rear end of the stem 14 is a crosshead 17 adapted to be engaged by the lower end of a latch-retracting lever 18 pivoted within the case at 19 and having a boss 19 adapted to be engaged by the rollback 12 so that the latch may be key-operated from the outside of the door.

In the casing are also mounted aligned hubs 20, only one of which is shown, which hubs receive the stems attached to the usual door knobs, not shown. In this instance the outer hub is dogged against movement by means of the lug 21 received in a recess 22 in an arm of the outer hub, so that the inner knob only is rotatable to retract the bolt 13. The inner hub carries a rollback 23 adapted to engage lugs 24 on a latch-retracting element or yoke 25, the yoke being urged to the left, as shown in Fig. 1, by the spring 26. At its upper end the yoke is provided with an extension 26a adapted to engage the crosshead 17 to withdraw the latch bolt when the inner knob is turned in either direction.

In the present instance the strike plate comprises an upper portion 28 and a lower portion 29, the latter being offset rearwardly and inwardly

from the former, as shown, for example, in Fig. 1. To the lower portion 28 is pivoted a slotted element 30 having an elongated slot 31 slightly enlarged at its upper end, as shown at 32. The element 30 is pivoted to the strike plate by a suitable fastening element 33 adjacent its upper end, so that it may swing from the full-line position shown in Fig. 5 to the dotted line position shown in that figure, or even to a further position, where it stands at right angles to the longitudinal dimension of the strike plate. It may be noted that the element 30 will normally stand directly below the portion 28 of the strike plate or within the vertical outline of this portion, so that the face of the element 30 is substantially flush with the element 28, as shown in Fig. 1.

The portion 28 of the strike plate is provided with the usual latch opening 35 to receive the bolt 13, while the lower portion of the plate is provided with a recess 36, which recess is relatively deep, as shown in Fig. 1, and as shown in Figs. 4 and 5 opens outwardly through the inner edge of this portion of the strike plate for a reason to be hereinafter set forth.

In the lock case is also provided a guard bolt 37 of more or less usual form, the guard bolt being adapted to be retracted by the strike plate when the door is closed against the action of the spring 33. The stem 39 of this bolt is provided at its rear end with a crosshead 40 which is adapted to engage the forward end of a lever 41 pivoted at 42 in the lock case, and having a rearwardly extending tail portion 43 provided in its lower edge with a notch 44 adapted to receive, in the position shown in Fig. 1, the upper end of the crosshead 17 so as to dog the latch bolt in protracted position. A spring 45 normally urges the lever to its operative position shown in Fig. 1, which it occupies when the door is closed. However, when the door is open and the guard bolt 37 no longer engages the strike plate, this bolt will be protracted by its spring 38 and the crosshead 40 on the bolt stem will engage the forward end of the lever 41 and swing this lever about its pivot 42 against the action of the spring 45, and thus move the tail 43 of the lever upwardly to disengage the crosshead 17 in the usual manner.

As will be understood, it is necessary to provide some means to move this dogging element to disengaging position when it is desired to open the door, and for this purpose the lever 41 is provided with a depending portion 46 which will be engaged by the upper lug 24 on the yoke 25, and thus move the tail portion 43 of the lever to inoperative position so that the latch bolt may be knob-operated when the door is closed.

In the lower part of the lock case is slidably mounted an auxiliary bolt or ajar hook bolt 50, this member being guided in its reciprocatory movements by a slot formed therein at 51 and a pin 52 carried by the lock case. The bolt has a rounded end portion 53 adapted to be protracted from the lock case, and in this portion is a latch member 54 pivoted at 55 and having lugs 56 and 57 at its front and rear ends, respectively. It will be noted that the latch member is overweighted at the forward or left-hand side of the pivot 55 so that when the bolt 50 is retracted the forward end of this latch will drop downwardly so that the lug 56 will stand substantially flush with the upper surface of the portion 53. However, when the bolt is protracted the lug 57 will engage the face plate 58 of the lock case and swing the latch element to the position shown in Fig. 7, wherein

the lug 56 protrudes upwardly from the slot in the bolt in which it normally stands.

It may here be stated that the head 53 of the auxiliary bolt is adapted to be protracted through the slot 31 of the swinging element 30 into the recess 36 of the strike plate, and when this occurs the opening of the door will be limited by the length of the slot 31 and the upstanding lug 56 on the pivoted element 54 will prevent the member 30 being forced from the end of the bolt head 53, as explained in my copending application.

A hub 60 is rotatably mounted in the lower portion of the lock case, and designed to be rotated by any suitable means, such as a thumb turn or knob, for example. To this hub is secured a rollback 61 which is pivoted at 62 to a link 63, the other end of which link is pivoted at 64 to the bolt 50, the members 61 and 63 forming an operating toggle for this bolt. A tension spring 65 secured at its forward end to the bolt and at its other end to the case will normally urge the bolt 50 to retracted position, this movement being prevented by the alignment of the toggle pivots when the bolt is thrown, as shown in Fig. 2.

Also secured to the hub 60 is an arm 66 adapted to stand in engagement with a depending member 67 on the yoke 25 when the bolt 50 is protracted, so that when the inner knob is turned to retract the yoke 25, the hub 60 will also be turned to retract the bolt 50. A second arm 68 is provided on this hub, which arm is adapted to engage below the turned end 69 of a slide member 70 mounted for vertical sliding movement in the lock case and having its upper end turned laterally, as shown at 71, so that it may be engaged by the rollback 61 to operate the hub 60 by depressing the arm 68 from the position shown in Fig. 2. This arrangement provides for a key operation of the hub 60 from the outside of the door, as well as operation of this hub by its own thumb turn (not shown), and by the usual door knob which operates the hub 20.

A lever 72 is pivoted in the case at 73 to serve as a walking beam between the latch bolt 13 and the auxiliary bolt 50. The lower end of this lever is engaged by a boss 74 on a portion of the bolt 50, while the upper end is provided with a slot 75 in which rests a pin 76 provided on a tail portion 77 of the bolt 13. It will be noted that this provides a one-way connection between the auxiliary bolt 50 and the lever 72, so that when the auxiliary bolt is in retracted position, as shown in Fig. 1, the latch bolt 13 may be operated freely to protracted or retracted positions without moving the bolt 50, the lever 72 swinging idly at this time. However, when the auxiliary bolt is protracted, as shown in Fig. 2, the latch bolt will be positively moved to retracted position and retained there against the action of its spring by the alignment of the toggle members 61 and 63.

It is desired to arrange to throw the auxiliary bolt when the door is in closed position, and it of course may be retracted into the case in any position of the door, whether open or closed. In order to throw the auxiliary bolt when the door is closed, an arrangement must be provided for moving the dogging lever 41 to inoperative position, for the latch bolt is always retracted when the auxiliary bolt is thrown, and when the door is closed the retraction of the guard bolt 37 permits the dogging lever 41 to assume an operative position. In order to effect this result, a slide 80 is mounted for vertical movement in the latch case, in this case adjacent the slide 70, and is pro-

vided with a recess or notch 81 adjacent its upper end to receive the end portion of the tail 43 of the lever 41, so that when the slide is moved upwardly the lever will also be moved upwardly to disengage the crosshead 17 of the latch bolt. At its lower end the slide member 80 is provided with a horizontally extending portion 82 having a shoulder 83 thereon adapted to be engaged by the arm 66, so that when the hub 60 is rotated in an anti-clockwise direction, as shown in Fig. 1, to protract the bolt 50, the slide 80 will be raised to permit retraction of the latch bolt.

It is desirable to have a lost-motion connection between the arm 66 and the slide 80 in view of the fact that after the dogging lever 41 has been moved to inoperative position it is necessary to continue the motion of the hub 60 to complete the protraction of the bolt 50. For this purpose the horizontally extending portion 82 of the slide 80 is provided with a recess 84 in which the end of the arm 66 rides after running off the shoulder 83, so that after the arm disengages the shoulder 83, it merely rides over the arcuate surface of the recess 84 without causing any additional upward movement of the slide 80. The arm 66 reaches its final position, shown for example in Fig. 2, at the time the auxiliary bolt 50 is fully protracted, the arm then being in position to be engaged by the portion 67 of the yoke, and stands against a shoulder 85 on the member 82.

From the foregoing it will be apparent that I have provided a door lock having a latch bolt arranged to be dogged in its protracted position to prevent anyone forcing an entry to the room which is guarded by the lock. At the same time I have arranged in the lock case an auxiliary or ajar bolt, so connected with the latch bolt that the latter is retracted when the auxiliary bolt is protracted, and at the same time the latch-bolt-dogging element is moved to inoperative position to permit the retraction of the latch bolt. It will also be understood that when the auxiliary bolt is protracted and connected with the swinging element 39, as shown for example in Fig. 3, this bolt may be retracted in any position of the door, either by rotation of the hub 60 or by rotation of the knob hub 20, or by a key at the outside of the door acting on the slide 70. When this bolt is retracted the parts are restored to their normal positions, the latch bolt being released for protraction by its spring 16.

Near the end 43 of the lever 41 a lug 90 is provided, which lug is adapted to be engaged by a lug 91 on the lever 18 to move the dogging lever 41 to inoperative position and permit key operation of the latch bolt by means of the lever 18.

While I have shown and described a preferred embodiment of my invention, it will be understood that it is not to be limited to all of the details shown, but is capable of modification and variation within the spirit of the invention and within the scope of the claims.

What I claim is:

1. A door lock comprising a case having a latch bolt therein adapted to cooperate with a strike plate, a guard bolt also cooperating with the strike plate, means controlled by the guard bolt to dog the latch bolt in protracted position when the door is closed and the guard bolt is pressed inwardly by the strike plate, an auxiliary bolt, means to protract the latter, an element slidably mounted in the case and actuated by said protracting means to move said dogging means to inoperative position, and a separate element actu-

ated by said protracting means to retract said latch bolt.

2. A door lock comprising a case having a latch bolt therein adapted to cooperate with a strike plate, a guard bolt also cooperating with the strike plate, means controlled by the guard bolt to dog the latch bolt in protracted position when the door is closed, an auxiliary bolt, means interconnecting said latch and auxiliary bolts to effect retraction of the former when the latter is protracted, and means to protract the auxiliary bolt and free the latch bolt from the dogging means.

3. A door lock comprising a case having a latch bolt therein adapted to cooperate with a strike plate, a guard bolt also cooperating with the strike plate, means controlled by the guard bolt to dog the latch bolt in protracted position when the door is closed, an auxiliary bolt, means interconnecting said latch and auxiliary bolts to effect retraction of the former when the latter is protracted, and means to protract the auxiliary bolt and free the latch bolt from the dogging means, said interconnecting means permitting free movement of the latch bolt when said auxiliary bolt is retracted.

4. A door lock comprising a case having a latch bolt therein adapted to cooperate with a strike plate, a guard bolt also cooperating with the strike plate, means controlled by the guard bolt to dog the latch bolt in protracted position when the door is closed, an auxiliary bolt, means to protract the latter, and a slide actuated by said protracting means and engaging said dogging means to move the latter to inoperative position.

5. A door lock comprising a case having a latch bolt therein adapted to cooperate with a strike plate, a guard bolt also cooperating with the strike plate, means controlled by the guard bolt to dog the latch bolt in protracted position when the door is closed, an auxiliary bolt, means to protract the latter, and an element actuated by said protracting means to move said dogging means to inoperative position, and said protracting means having a lost-motion connection with said element.

6. A door lock comprising a case having a latch bolt therein adapted to cooperate with a strike plate, a guard bolt also cooperating with the strike plate, means controlled by the guard bolt to dog the latch bolt in protracted position when the door is closed, an auxiliary bolt, means to protract the latter, said protracting means comprising a hub having an arm, a slide mounted in the case having a lost-motion connection with said arm, and said slide engaging said dogging means to move the latter to inoperative position.

7. A door lock comprising a case having a latch bolt therein adapted to cooperate with a strike plate, a guard bolt also cooperating with the strike plate, means controlled by the guard bolt to dog the latch bolt in protracted position when the door is closed, an auxiliary bolt, means to protract the latter, means to effect retraction of the latch bolt upon protraction of the auxiliary bolt, and additional means to actuate the latch bolt, said means also serving to retract the auxiliary bolt.

8. A door lock comprising a case having a latch bolt therein adapted to cooperate with a strike plate, a guard bolt also cooperating with the strike plate, means controlled by the guard bolt to dog the latch bolt in protracted position when the door is closed, an auxiliary bolt, means to protract the latter, means to effect retraction of the latch bolt upon protraction of the auxiliary

bolt, and key-operated means to retract the auxiliary bolt.

9. In a door holder, a case having a latch bolt and an auxiliary bolt reciprocably mounted therein, said latch bolt being adapted to cooperate with a strike plate, an element movably mounted on the door jamb with which said auxiliary bolt cooperates to hold the door in partly open position, a guard bolt in the case cooperating with the strike plate, means controlled by the guard bolt to dog the latch bolt against movement when the door is closed, and means to protract said auxiliary bolt and simultaneously move said dogging means to inoperative position and retract the latch bolt.

10. In a door holder, a case having a latch bolt and an auxiliary bolt reciprocably mounted therein, said latch bolt being adapted to cooperate with a strike plate, an element movably mounted on the door jamb with which said auxiliary bolt cooperates to hold the door in partly open position, a guard bolt in the case cooperating with the strike plate, means controlled by the guard bolt to dog the latch bolt against movement when the door is closed, means to protract said auxiliary bolt and engage it with said element when the door is closed, and a connection between said protracting means and said dogging means to move the latter to inoperative position.

11. In a door holder, a case having a latch bolt and an auxiliary bolt reciprocably mounted therein, said latch bolt being adapted to cooperate with a strike plate, an element movably

mounted on the door jamb with which said auxiliary bolt cooperates to hold the door in partly open position, a guard bolt in the case cooperating with the strike plate, means controlled by the guard bolt to dog the latch bolt against movement when the door is closed, means to protract said auxiliary bolt and engage it with said element when the door is closed, and a connection between said protracting means and said dogging means to move the latter to inoperative position, said latch and auxiliary bolts being interconnected whereby the former is retracted when the latter is protracted.

12. In a door holder, a case having a latch bolt and an auxiliary bolt reciprocably mounted therein, said latch bolt being adapted to cooperate with a strike plate, an element movably mounted on the door jamb with which said auxiliary bolt cooperates to hold the door in partly open position, a guard bolt in the case cooperating with the strike plate, means controlled by the guard bolt to dog the latch bolt against movement when the door is closed, means to protract said auxiliary bolt and engage it with said element when the door is closed, a connection between said protracting means and said dogging means to move the latter to inoperative position, said latch and auxiliary bolts being interconnected whereby the former is retracted when the latter is protracted, and knob-operated means to retract both said bolts.

HENRY G. VOIGHT.
